United States Patent

Des. 241,801
Patented Oct. 12, 1976

241,801

DESSERT CUP

Albert E. Colato, St. Paul, Minn., assignor to
American Dairy Queen Corp.

Continuation of abandoned design application Ser. No.
392,661, Aug. 29, 1973. This application June 26, 1975,
Ser. No. 590,620

Term of patent 14 years

Int. Cl. D7—01

U.S. Cl. D7—14

fig. 1.

fig. 3.

fig. 2.

fig. 4.

fig. 5.fig. 7.fig. 6.fig. 8.FIG. 1 is a side elevational view of a dessert cup showing my new design;

FIG. 2 is a top plan view thereof showing the internal ribs formed therein;

FIG. 3 is a vertical sectional view taken along the line 3-3 in FIG. 2;

FIG. 4 is a bottom plan view thereof;

FIG. 5 is a side elevational view of a modification of my dessert cup of FIG. 1;

FIG. 6 is a top plan view of FIG. 5;

FIG. 7 is a vertical sectional view taken along line 7-7 of FIG. 6; and

FIG. 8 is a bottom plan view of FIG. 5.

The stippled shading represents contrast in texture.

This is a continuation of design application Ser. No. 392,661, filed Aug. 29, 1973, now abandoned.

I claim:

The ornamental design for a dessert cup, as shown and described.
